UNITED STATES PATENT OFFICE.

WILLIAM E. MOORE, OF CHICAGO, ILLINOIS, ASSIGNOR, BY MESNE ASSIGNMENTS, TO INTERNATIONAL EARTH-BORING MACHINE CORPORATION, A CORPORATION OF DELAWARE.

METHOD OR PROCESS OF OPERATING AUGERS.

1,363,049.

Specification of Letters Patent. Patented Dec. 21, 1920.

Application filed November 13, 1919. Serial No. 397,726.

To all whom it may concern:

Be it known that I, WILLIAM E. MOORE, a citizen of the United States, residing at Chicago, in the county of Cook and State of Illinois, have invented certain new and useful Improvements in Methods or Processes of Operating Augers, of which the following is a specification.

This invention relates to a method or 10 process of operating augers.

It is particularly advantageous in the boring of holes in the earth.

Heretofore it has been the practice, in 15 the operation of earth boring augers, to manually remove the earth from the auger or to provide mechanical scrapers and conveyers for automatically freeing the auger from its load. These methods require long and arduous manual labor or the provision 20 of more or less complicated mechanism which is always liable to clog, break or otherwise prove troublesome, expensive and unsatisfactory.

One of the objects of this invention is to 25 provide an improved method of operating augers.

Another object is to provide an improved method of boring holes in the earth.

Another object is to provide a method 30 whereby both manual labor and mechanical complication are reduced to a minimum.

Other objects and advantages will appear from the specification and claims.

In general the method comprehends the 35 advancement of the auger while it is being rotated at one speed, and accelerating the rotation of the auger during or after its withdrawal to throw off the load by centrifugal action.

40 The method will be described in connection with the accompanying drawings which illustrate one form of boring machines that may be employed.

In the drawings—

45 Figure 1 is a side elevation, partly in section, of an earth boring machine.

Fig. 2 is a top plan thereof, and

Fig. 3 is an end elevation of a part of the auger driving mechanism.

50 The earth boring machine shown in the drawings is of the portable type, being mounted upon a motor truck. The engine of the truck furnishes the power for operating the auger. Most of the construction

details are omitted from the drawings, because the method hereinafter described does not depend upon and is not peculiar to any particular type of machine. The structure of an earth boring machine which has been found to give excellent results in the practice of the present process is disclosed in my copending application Serial No. 292,133 filed April 23, 1919.

In general the earth boring machine comprises an auger tower 5 within which is located an auger shaft 6, carrying at its lower end an earth boring auger 7. The auger tower is mounted upon a turntable 8 rotatably carried upon the chassis of the truck. By means of the turntable the auger can be accurately positioned above the place where a hole is to be made.

The drive shaft of the engine of the truck is connected, by a sprocket wheel and chain connection 9, to a counter shaft 10. Shaft 10, through suitable beveled gear trains and a vertical shaft on the axis of the turntable drives a counter shaft 11. Shaft 11 is journaled in suitable bearings 12 and 13, mounted on the turntable. Through shaft 11 the engine furnishes the power for rotating and for elevating and lowering the auger.

The engine rotates the auger always in the same direction. Shaft 11 has a bevel gear wheel 15 keyed thereto. Gear wheel 15 drives a gear wheel 16 keyed to a shaft 17. Shaft 17 extends across the turntable and has keyed thereto a clutch member 18. Clutch member 18 is adapted to slide on shaft 17 into and out of driving connection with a co-operating clutch member 19 which forms a part of a sprocket wheel 20 loosely journaled on shaft 17. Clutch members 18 and 19 are thrown into and out of driving position by an operator's lever 21.

Sprocket wheel 20, through a chain 25 drives a sprocket wheel 26, keyed to a shaft 27 journaled on the turntable. Shaft 27 has a beveled pinion 28 keyed thereto and this pinion engages a co-operating beveled gear 100 wheel 29. Gear wheels 27 and 28 are mounted in a gear box 30 which supports the auger tower and through which the auger shaft passes. Gear wheel 29 is provided with a square opening through which auger shaft 6, which is also of square cross-section, is longitudinally slid able. Thus the rotation of gear wheel 29 rotates the auger shaft and

auger in any position of the auger or while the auger is being raised and lowered.

The engine also acts to raise and lower the auger. Shaft 11, in addition to gear 5 wheel 15, also has a beveled gear wheel 33, secured thereto and engaging a bevel gear wheel 34 loosely mounted on a sleeve encircling shaft 17. This sleeve has a sprocket wheel 35 and a double acting clutch member 10 36 keyed thereto. A beveled gear wheel 37 loosely journaled on this sleeve engages gear wheel 15.

When clutch member 36 is moved in one direction, it coöperates with a clutch member 15 on gear wheel 34 and the sleeve and sprocket wheel 35 are driven in one direction. When the position of clutch member 36 is reversed, it engages a clutch member 20 on gear wheel 37 and the sleeve and sprocket wheel 35 are driven in the reverse direction. Clutch member 36 is controlled by an operator's lever 38.

Sprocket wheel 35, through a chain 40, drives a sprocket wheel 41 loosely journaled 25 on shaft 27. Sprocket wheel 41 is rigidly connected to a sprocket wheel 42 also loosely journaled on shaft 27. Through chain 43 and a sprocket wheel 44 sprocket wheel 42 drives a shaft 45 journaled to the auger 30 tower near its bottom. Shaft 45 carries a sprocket wheel 46 keyed thereto. A chain 48 passes over sprocket wheel 46 and a similar sprocket wheel 49' which is located near 35 the top of the tower. Chain 48 is secured to auger shaft 6 by a coupling 49, the coupling being of such construction that the shaft is free to rotate.

Thus the auger shaft and auger are raised and lowered, depending upon the position 40 of lever 38, by sprocket wheel 35, chain 40, sprocket wheels 41 and 42, chain 43, sprocket wheels 44 and 46, and chain 48.

In practising the process the auger is positioned above the place where a hole is to be 45 bored. Then levers 21 and 38 are thrown to start the rotation and downward travel of the auger. The speed of rotation of the auger is regulated in any desired manner, such for example as by controlling the speed 50 of the engine, to best suit the soil and other conditions, the auger enters and progresses into the earth and accumulates its load.

When the desired depth of hole is reached or in the case of extremely heavy and sticky

soil the auger has penetrated to about the 55 limit of the extent of its best operation, lever 38 is thrown to cause the raising of the auger. As the auger emerges from the hole or after it is completely removed therefrom 60 its rotation is accelerated in any desired manner, as by speeding up the engine. The higher speed of rotation increases the centrifugal action tending to throw off or expel the load of earth elevated by the auger. The speed of rotation may be increased to such 65 an extent that the earth is thrown or expelled from the auger and clear of the hole. When the auger is completely freed of earth its speed of rotation may be decreased and, if the hole is not of the desired depth, the 70 boring operation may proceed.

This method of operating augers and boring holes has been found to give excellent results. No scrapers, conveyors or arduous manual labor are required to free the auger 75 of its load. The earth is readily expelled by centrifugal action and a clean hole is quickly and advantageously provided.

Having described my invention, what I claim is:—

1. The method of operating augers which comprises, advancing the auger at one speed of rotation, and subsequently accelerating the rotation of the auger to expel the load by 80 centrifugal action.

2. The method of boring holes in the earth which comprises, advancing the auger into the earth at one speed of rotation; withdrawing the auger with its load of earth, and rotating the auger at a higher speed to 85 expel the load by centrifugal action.

3. The method of boring holes which comprises, loading the auger, withdrawing the auger from the hole produced in the loading thereof, and expelling the load from the 90 auger by the effect of centrifugal action.

4. The method of boring holes in the earth which comprises, advancing the auger to bore the hole, loading the auger during the 100 boring operation, withdrawing the auger and its load of earth from the hole, and rotating the auger at a higher speed than required to bore the hole to clear the auger of its load of earth.

In testimony whereof I hereunto subscribe my name.

WILLIAM E. MOORE.
